UNITED STATES PATENT OFFICE

2,595,851

ELECTRICAL PULL-CORD SOCKET

Otto Holzapfel, Chicago, Ill.

Application June 1, 1951, Serial No. 229,379

11 Claims. (Cl. 200—51.15)

1

This invention relates generally to improvements in electrical pull-cord sockets and is particularly directed to the provision of a pull-cord socket having a novel and unique switch mechanism through which current passes completely insulated from the rotating parts thereof and the pull-cord whereby to insure safe operation and long life.

The principal objects of the invention consist of the provision of an electrical pull-cord socket in which short circuiting of the socket because of heating up of the cord or entanglement thereof with the rotating parts of the socket substantially will be eliminated; in which the occurrence of fires or shock to persons handling same will be materially reduced; which may be installed or replaced easily and simply without requiring great skill or training; which is inexpensive to manufacture, fool-proof against short circuiting and eliminates the use of open wires therein.

Still another important object of the invention is to provide a pull-cord socket of the character described having a novel switch mechanism in which the rotatable parts of the same are enclosed and totally insulated from the electrical parts of the switch.

Still a further object of the invention is to provide a socket of the character described having a novel mechanism for actuating a switch operating pin.

With the foregoing and other objects in view which will appear as the description proceeds, the invention consists of certain novel features of construction, arrangement and a combination of parts hereinafter fully described, illustrated in the accompanying drawings, and particularly pointed out in the appended claims, it being understood that various changes in the form, proportion, size and minor details of the structure may be made without departing from the spirit or sacrificing any of the advantages of the invention.

For the purpose of facilitating an understanding of this invention, there is illustrated in the accompanying drawings a preferred embodiment thereof, from an inspection of which, when considered in connection with the following description, this invention, its mode of construction, assembly and operation, and many of its advantages should be readily understood and appreciated.

Referring to the drawings in which the same characters of reference are employed to indicate corresponding or similar parts throughout the several figures of the drawings:

Fig. 1 is a side elevational view of an electrical

2

pull-cord socket of the type with which the invention is concerned.

Fig. 2 is a vertical sectional view taken through an electrical pull-cord socket having the invention embodied therein.

Fig. 3 is a sectional view taken through the socket along the line 3—3 of Fig. 2 and in the direction indicated.

Fig. 4 is a sectional view taken along the line 10 4—4 of Fig. 3 and in the direction indicated.

Fig. 5 is a perspective view of the contact arm used in the socket embodying the invention.

Fig. 6 is a sectional view through the socket taken along the lines 6—6 of Fig. 2 and in the 15 direction indicated.

Fig. 7 is an elevational view taken along the line 1—7 of Fig. 3 and in the general direction indicated, portions being broken away to show details.

20 Fig. 8 is a sectional view taken along the line 8—8 of Fig. 3 and in the direction indicated.

Fig. 9 is a vertical sectional view taken through a portion of the socket and showing certain details of construction illustrated in Fig. 3 on an 25 enlarged scale.

Fig. 10 is a perspective view of the ratchet wheel used in the socket embodying the invention.

Generally, in devices of the character herewith concerned, current drawn from a power line 30 is passed through the socket to energize an electric lamp or other device screwed into or connected to one end thereof. In order to permit alternate ignition and shutting off of the lamp, a switch mechanism is interposed in the circuit

35 between one side of the power line and the electric lamp, the switch being operated by means of a pull-cord secured to the switch and having a portion thereof disposed on the outside of the socket. It has been found in prior art sockets

40 that after prolonged use of the lamp, the socket heats up, thereby causing the pull-cord also to heat up. In other instances, the pull-cord may become entangled in rotating parts of the switch whereby to cause a short circuit. Fires and

45 shocks to persons handling the socket have occurred repeatedly and a skilled technician is required to be summoned in order to replace or install prior art sockets of the character herewith concerned. All of these disadvantages substantially are eliminated by means of the herein-described invention.

50 Referring now to the drawings, the reference character 20 designates generally an electrical pull-cord socket of the type herein concerned.

Fig. 1 is a side elevational view of an electrical

Same includes a hollow casing cylindrical in form, which is adapted to contain the operating parts of the socket and is formed from a cap member 22 and an outer casing 23 having cooperating screw threads 24 adapted to be matingly engaged. A power line 25 is received in an opening 26 provided in the crown of the cap 22 and an electric lamp 27 is removably secured in the lower end 28 of the member 22. A pull-cord 29 extends from said casing for operating said lamp.

The cap member is provided with contacts to which the leads of the power line are secured. Referring to Fig. 2, there is disposed in the cap an insulating plug 30 having vertical elongate recesses 31 and 31' arranged diametrically one with the other. The above referred to contacts comprise metal plates 32 and 32' arranged over the openings on the upper surface of the plug 30 as viewed in Fig. 3, and each plate has an offset perforation for receiving therein binding post screws in a manner well-known in the art. The bared ends 33 and 33' of the leads 34 and 34' of the power line are held in engagement with the respective contacts 32 and 32' by means of binding post screws 35 which pass through the perforations (not shown) and are threaded into the plug 30 thereby holding the contacts 32 and 32' and the bared ends 33 and 33' firmly against the plug surface. It is not believed necessary to enter into great detail concerning this arrangement since it is well-known, and there are many additional ways of securing the contacts physically to the plug 30 and electrically to the leads.

The lower end 28 of the outer housing 23 is of reduced diameter and provides a socket into which the lamp 27 is received. A threaded sheet metal shell 38 is secured on the inside of the portion 28. The shell has the usual convolutions on the interior thereof to form threads 39 for reception of the lamp base. The shell has integrally formed flanges or ears 40 and 41, diametrically disposed on the upper end thereof as viewed in Fig. 2 for fastening the shell to the bottom end of the inner housing as will be explained.

Disposed within the outer casing 23 is a housing 42 in which the operating parts of the socket 20 are contained. Said housing 42 may be made from phenolic resin or some other non-conducting material and includes a pair of spaced vertical walls 43 and 44, a top wall 45 and a bottom wall 46, said walls being suitably joined to form therebetween a central cavity 47. The bottom wall 47 is disposed adjacent the ears 40 and 41, while the top wall is adapted to engage the plug 30. The switch mechanism designated generally 48 is contained in the cavity 47 with means being provided for completing the circuit between the leads 34, 34' and the shell 38.

Referring to Fig. 3, there is shown the construction for completing the circuit between the switch 48 and the leads 34, 34'. In the top wall 45 is provided a pair of spaced recesses 49 and 49', each having an enlarged bore 50 and a narrower bore 51, said bores 51 each communicating with the upper surface 52 of wall 45. A metallic contact prong 53 is disposed in the recess 49 and similar prong 53' is arranged in recess 49'. Each of said prongs has a flange 54 on one end thereof while the opposite ends thereof are arranged to enter the recesses 31 and 31' respectively to engage with contacts 32 and 32'. In order to maintain engagement of the prongs against the contacts, there is provided a pair of coil springs 56 and 56', one spring 56 being con-

tained in the bore 50 of recess 49 between the lug 54 and wall 45 and the other spring 56' being contained in bore 50 of recess 49' in the same position. Thus, the springs 56, 56' serve to urge the respective prongs 53, 53' upward into engagement with its respective contact 32, 32'.

It is noted that the left hand prong 53 is of larger diameter than the prong 53' and likewise the left hand recess 31 is of a larger diameter to accommodate this larger prong. In this manner, the rounded wire 33 will be positively connected with the shell 38 while the "hot" wire 33' will be the one opened when the switch 48 is operated. This will thereby provide an additional safety factor in my device.

Secured to the exterior of wall 44 is an L-shaped conductor strip 58, one arm 59 being secured to the wall 44 by a screw 60, while the other arm 61 is inserted through wall 44, into recess 49' and beneath the end of spring 56'. Thus, the lead 34' is electrically connected through contact 32' to prong 53' and spring 56' to the strip 58. On arm 59 is secured a contact button 62 extending outwardly therefrom. To complete the circuit from the strip 58 to the ear 41, I provide a flat, resilient metallic strip 63 secured also to the outer surface of wall 44. Said strip 63 has a contact button 64 secured to the surface 65 at the upper end of said strip adapted to contact the button 62. The lower end of the strip 63 is bent as at 66 to extend across the bottom of wall 46, and thence partially into the shell 38. The strip 63 is secured to the wall 44 immediately above said bend 66 by means of a flat plate 70 mounted thereover and screws 71 threaded into the wall 44. The plate 70 is slotted at 66 to permit its being adjusted to change the tension in the member 63.

Mounted on the wall 43 is a C-shaped metallic strip 73 having an upper arm 74 and a lower arm 75 connected by a straight portion 76. The arm 74 is disposed beneath the spring 56 in contact therewith, while the arm 75 is arranged above the ear 40 in contact therewith. Thus, the circuit from lead 34 to the ear 40 is through contact 32, prong 53, spring 56 and metallic strip 73. Screws 67 secure ears 40 and 41 to the bottom wall 46, and one passes through arm 75. When the lamp is screwed into the socket, the end 67' of the strip 63 will remain biased into contact with one terminal of the lamp thereby completing the circuit from ear 41 to said end through shell 38 and the lamp.

We will now consider the construction of the switch mechanism 48. Same comprises a shaft 76 journaled for rotation in walls 43 and 44 and having a headed end 77 disposed in recess 78 of the wall 43. Mounted on shaft 76 is a sleeve member 79 having an enlarged diameter portion 80 and a narrower portion 81, said sleeve member 79 having its ends engaged against the inside of walls 43 and 44 respectively. A ratchet device is mounted on said shaft which includes a collar 82 mounted on the portion 80, said collar being made from plastic or other insulating material, said collar has a channel 83 along the periphery thereof defined by the spaced upstanding walls 84 and 85. A pin 86 secured between walls 84 and 85 extends into the channel 83. The end 87 of a coil spring 88 is secured to said pin 86, while the second end 89 of said spring is secured to one of the screws 71 as shown in Fig. 2. The end 90 of the pull-cord 29 also is attached to said pin 86, said cord extending through an opening 91 in the housing 23 to a point exterior thereof. Thus, by

pulling the cord 29 to the right as viewed in Fig. 2, the collar 82 will be caused to rotate in a clockwise direction, expanding the spring 88. Upon release of the cord 29, the spring in returning to its normal direction will rotate the collar in a counter-clockwise direction. Obviously the cord 29 may be a metal bead-chain or the like as common to such device.

Mounted on the narrow portion 81 of the sleeve member is a ratchet wheel 92 best shown in Fig. 10. The ratchet 92 preferably is made from plastic or other suitable non-conducting material. The side 93 of said ratchet has formed thereon a series of steps or teeth 94 each consisting of a flat portion 95 tapered inwardly and terminating in a shoulder portion 96 perpendicular to the vertical axis of the ratchet. The side 97 is formed with a series of steps or cam formations 98 terminating in shoulder portions 99 perpendicular to the vertical axis of said ratchet. The cam formations are formed so that alternate ones have deeper indentations than intermediate ones. The number of cam formations are equal to the number of steps 94.

When the ratchet wheel is mounted on the narrow portion 81 the side 93 is disposed adjacent the wheel 82 and the side 97 is disposed adjacent the wall 44.

The ratchet 92 is adapted to be rotated simultaneously with rotation of the wheel 82. Accordingly, I provide a pair of detents 103 and 101 secured to the exterior of wall 84 and protruding therefrom to engage against the side 93 of the ratchet. To maintain the wheel 82 and ratchet 92 in proper position relative to each other, there is provided a spring 102 having its ends 103 and 104 engaged respectively against the walls 45 and 46 with the body portion of said spring biased against the wheel 82 as at 105.

Mounted in an opening 106 in wall 44 is a reciprocable push rod 107 made from a non-conducting material such as plastic or the like. Said rod 107 is longer than the width of said wall 44 and has one end 108 disposed outside of said wall and adapted to engage the metallic strip 63. The other end 109 is disposed in the cavity 47 and against the side 97 of the ratchet 92. The rod 107 serves to break the contact between the contact buttons 62 and 64.

The operation of the socket constituting my invention is as follows. Referring to Fig. 9, with the button 64 in contact with the button 62, the circuit from the leads 34 and 34' to the ears 40 and 41 is closed and the lamp will be ignited. In this condition, the rod 107 will have its end 109 disposed against the side 97 of ratchet wheel 92, and the end 108 will be free of the strip 63. To break the circuit the pull-cord 27 is drawn outward whereby the end 90 of said cord will exert a force on the pin 86 rotating the wheel 82 in a clockwise direction. The detents 100 and 101 will engage against a shoulder 96 and rotate therewith the ratchet 92. Upon rotation of the ratchet 92, the end 109 of the plug 107 will be caused to ride up the inclined surfaces of the conformations 98 and be moved to the right as viewed in Fig. 10 against the strip 63. Continued movement of the rod 107 to the right will push the resilient strip 63 to the right to move the button 64 out of contact with the button 62 breaking the circuit and shutting off the lamp 27. Continued rotation of the ratchet wheel 92 will cause the rod 107 to drop off a shoulder 99 and the cord 29 is released so that the spring 88 will return the wheel 82 to a position where the detents 100 and 75

101 engage against the next shoulders 96. To ignite the lamp the pull-cord is again pulled outwardly to turn the wheel 82 and the ratchet 92. Because the cam formations 98 are alternately deeper and shallower, when the rod 107 is engaged on a shallower formation, the buttons 62 and 64 will be out of contact whereas when the rod 107 is engaged against in a deeper formation, the buttons will be in contact one with the other to ignite the lamp. It will be appreciated that the cam formation 98 may be formed as upward steps just as well in order to reciprocate the rod 107.

Since the collar 82 and ratchet wheel 92 are made of non-conducting material, it will be seen that the cord 27 will not be liable to being heated during operation of the lamp nor will the socket short circuit should the said cord become entangled in the operating parts. Also, by mounting the conductor strips 73, 58 and the resilient strip 63 on the exterior of the housing 42 and removed from the rotating parts 82 and 92, the likelihood of short circuiting, fires and electrocution is substantially eliminated. Replacement and installation of the socket device is easily and rapidly accomplished without requiring great technical skill.

The operation of the cap 22 in being attached to the body of the device is believed obvious. Suffice it to say that the cap is rotatable relative to the remainder of the socket so that the prongs can be engaged in proper relationship with the respective recesses and the cap screwed home. Thus it is possible to change completely the sockets without disturbing the permanent wiring of the building or the line.

It is believed that this invention, its mode of construction and assembly, and many of its advantages should be readily understood from the foregoing without further description, and it should also be manifest that while a preferred embodiment of the invention has been shown and described for illustrative purposes, the structural details are nevertheless capable of wide variation within the purview of this invention as defined in the appended claims.

What is claimed and desired to be secured by Letters Patent of the United States is:

1. An electrical pull-cord connector for establishing electrical circuit between a line and an electrical device, comprising an insulating casing having a fixed and a movable contact on the outside thereof, the movable contact being biased into engagement with the fixed contact, each contact being connected to a part of the circuit and said contacts when engaged adapted to establish said circuit, a ratchet device in the casing and a pull cord connected with the ratchet device and extending outside of the casing and adapted when pulled to operate the said ratchet device, said ratchet device including a uni-directional rotatable wheel having ratchet teeth whereby the successive pulls of the cord will rotate the wheel in step-by-step movements, each step being a fraction of a revolution, said wheel having cam formations corresponding in number to the number of ratchet teeth, a reciprocable member extending through the casing and having one end engaging the movable contact outside of the casing and the other end engaging a cam formation of said wheel, the alternate cam formations being of a dimension to position the reciprocable member to move the movable contact free of the fixed contact, while

the intermediate conformations being of a different dimension disposing the reciprocal member in a position permitting the contacts to engage, whereby successive pulls of the cord will make and break said circuit.

2. An electrical pull-cord connector for establishing electrical circuit between a line and an electrical device, comprising an insulating casing having a fixed and a movable contact on the outside thereof, the movable contact being biased into engagement with the fixed contact, each contact being connected to a part of the circuit and said contacts when engaged adapted to establish said circuit, a ratchet device in the casing and a pull cord connected with the ratchet device and extending outside of the casing and adapted when pulled to operate the said ratchet device, said ratchet device including a uni-directional rotatable wheel having ratchet teeth whereby the successive pulls of the cord will rotate the wheel in step-by-step movements, each step being a fraction of a revolution, said wheel having cam formations corresponding in number to the number of ratchet teeth, a reciprocal member extending through the casing and having one end engaging the movable contact outside of the casing and the other end engaging a cam formation of said wheel, the alternate cam formations being of a dimension to position the reciprocal member to move the movable contact free of the fixed contact, while the intermediate conformations being of a different dimension disposing the reciprocal member in a position permitting the contacts to engage, whereby successive pulls of the cord will make and break said circuit, said device being made from a non-conducting material whereby current passing through the connector will be insulated from said pull-cord.

3. An electrical pull-cord connector for establishing electrical circuit between a line and an electrical device, comprising an insulating casing having a fixed and a movable contact on the outside thereof, the movable contact being biased into engagement with the fixed contact, each contact being connected to a part of the circuit and said contacts when engaged adapted to establish said circuit, a ratchet device in the casing and a pull cord connected with the ratchet device and extending outside of the casing and adapted when pulled to operate the said ratchet device, said ratchet device including a uni-directional rotatable wheel having ratchet teeth whereby the successive pulls of the cord will rotate the wheel in step-by-step movements, each step being a fraction of a revolution, said wheel having cam formations corresponding in number to the number of ratchet teeth, a reciprocal member extending through the casing and having one end engaging the movable contact outside of the casing and the other end engaging a cam formation of said wheel, the alternate cam formations being of a dimension to position the reciprocal member to move the movable contact free of the fixed contact, while the intermediate conformations being of a different dimension disposing the reciprocal member in a position permitting the contacts to engage, whereby successive pulls of the cord will make and break said circuit, said device including a spring biased rotatable member disposed adjacent said wheel and having detents engageable with said teeth, said pull-cord being attached to said member for simultaneously rotating said member and said wheel.

4. An electrical pull-cord connector for estab-

lishing electrical circuit between a line and an electrical device, comprising an insulating casing having a fixed and a movable contact on the outside thereof, the movable contact being biased into engagement with the fixed contact, each contact being connected to a part of the circuit and said contacts when engaged adapted to establish said circuit, a ratchet device in the casing and a pull cord connected with the ratchet device and extending outside of the casing and adapted when pulled to operate the said ratchet device, said ratchet device including a uni-directional rotatable wheel having ratchet teeth whereby the successive pulls of the cord will rotate the wheel in step-by-step movements, each step being a fraction of a revolution, said wheel having cam formations corresponding in number to the number of ratchet teeth, a reciprocal member extending through the casing and having one end engaging the movable contact outside of the casing and the other end engaging a cam formation of said wheel, the alternate cam formations being of a dimension to position the reciprocal member to move the movable contact free of the fixed contact, while the intermediate conformations being of a different dimension disposing the reciprocal member in a position permitting the contacts to engage, whereby successive pulls of the cord will make and break said circuit, said device including a spring biased rotatable member disposed adjacent said wheel and having detents engageable with said teeth, said pull-cord being attached to said member for simultaneously rotating said member and said wheel, said reciprocal member comprising a push rod formed of non-conducting material.

5. An electrical pull-cord connector for establishing electrical circuit between a line and an electrical device, comprising an insulating casing having a fixed and a movable contact on the outside thereof, the movable contact being biased into engagement with the fixed contact, each contact being connected to a part of the circuit and said contacts when engaged adapted to establish said circuit, a ratchet device in the casing and a pull cord connected with the ratchet device and extending outside of the casing and adapted when pulled to operate the said ratchet device, said ratchet device including a uni-directional rotatable wheel having ratchet teeth whereby the successive pulls of the cord will rotate the wheel in step-by-step movements, each step being a fraction of a revolution, said wheel having cam formations corresponding in number to the number of ratchet teeth, a reciprocal member extending through the casing and having one end engaging the movable contact outside of the casing and the other end engaging a cam formation of said wheel, the alternate cam formations being of a dimension to position the reciprocal member to move the movable contact free of the fixed contact, while the intermediate conformations being of a different dimension disposing the reciprocal member in a position permitting the contacts to engage, whereby successive pulls of the cord will make and break said circuit, and a plate member adjustably mounted over said movable contact whereby to permit the tension of said contact to be varied.

6. An electrical pull-cord connector for completing an electrical circuit between a line and an electrical device, comprising an insulating housing having a fixed and movable contact on the outside thereof, the movable contact being biased into engagement with the fixed contact,

each contact being connected to a part of the circuit and said contacts when engaged adapted to complete said circuit, a ratchet device in the housing including a spring biased detent member having said pull-cord attached thereto with the pull-cord extending outside of the casing, and a uni-directional ratchet wheel having ratchet teeth disposed in engagement with said member whereby successive pulls of said cord will rotate the wheel in step-by-step movements, each step being a fraction of a revolution, said wheel having cam formations corresponding in number to the number of teeth, a reciprocable push rod mounted in a wall of said casing and having one end engaging the movable contact outside of the casing and the other end engaging a cam formation, the alternate cam formations being of a dimension to move said rod for freeing the movable contact from the fixed contact, while the intermediate cam formations being of a different dimension permitting the rod to be moved away from said movable contact disposing the contacts in engagement with each other, whereby successive pulls of the cord will make and break the circuit.

7. An electrical pull-cord connector for completing an electrical circuit between a line and an electrical device, comprising an insulating housing having a fixed and movable contact on the outside thereof, the movable contact being biased into engagement with the fixed contact, each contact being connected to a part of the circuit and said contacts when engaged adapted to complete said circuit, a ratchet device in the housing including a spring biased detent member having said pull-cord attached thereto with the pull-cord extending outside of the casing, and a uni-directional ratchet wheel having ratchet teeth disposed in engagement with said member whereby successive pulls of said cord will rotate the wheel in step-by-step movements, each step being a fraction of a revolution, said wheel having cam formations corresponding in number to the number of teeth, a reciprocable push rod mounted in a wall of said casing and having one end engaging the movable contact outside of the casing and the other end engaging a cam formation, the alternate cam formations being of a dimension to move said rod for freeing the movable contact from the fixed contact, while the intermediate cam formations being of a different dimension permitting the rod to be moved away from said movable contact disposing the contacts in engagement with each other, whereby successive pulls of the cord will make and break the circuit, said detent member and wheel being formed from non-conducting material whereby current passing through the connector will be insulated from the cord.

8. An electrical pull-cord connector for completing an electrical circuit between a line and an electrical device, comprising an insulating housing having a fixed and movable contact on the outside thereof, the movable contact being biased into engagement with the fixed contact, each contact being connected to a part of the circuit and said contacts when engaged adapted to complete said circuit, a ratchet device in the housing including a spring biased detent member having said pull-cord attached thereto with the pull-cord extending outside of the casing, and a uni-directional ratchet wheel having ratchet teeth disposed in engagement with said member whereby successive pulls of said cord will rotate the wheel in step-by-step movement, each step

being a fraction of a revolution, said wheel having cam formations corresponding in number to the number of teeth, a reciprocable push rod mounted in a wall of said casing and having one end engaging the movable contact outside of the casing and the other end engaging a cam formation, the alternate cam formations being of a dimension to move said rod for freeing the movable contact from the fixed contact, while the intermediate cam formations being of a different dimension permitting the rod to be moved away from said movable contact disposing the contacts in engagement with each other, whereby successive pulls of the cord will make and break the circuit, said detent member and wheel being formed from non-conducting material whereby current passing through the connector will be insulated from the cord, said rod being made from a non-conducting material.

9. In an electrical pull-cord socket of the character described including an insulating housing adapted to contain a switch mechanism for making and breaking an electrical circuit between a line and an electrical device, a switch mechanism including a fixed and movable contact mounted on the outside of said housing, the movable contact being biased into engagement with the fixed contact, each contact being connected to a part of the circuit and said movable contact being movable relative to said fixed contact for making and breaking the circuit, a rotatable detent member having the pull-cord thereto attached, a unidirectional rotatable wheel having ratchet teeth engageable by said member adapted to rotate the wheel in step-by-step movements with successive pulls of the cord, said wheel having a plurality of cam formations corresponding in number to the number of ratchet teeth, a reciprocable rod mounted in a wall of said casing having one end engaging the movable contact outside the casing and the other end engaging a cam formation, said cam formations being of a dimension whereby alternate formations will cause said rod to be moved against said movable contact for moving said contact out of engagement with the fixed contact while intermediate formations permit movement of the rod in a direction permitting said movable contact to engage the fixed contact, whereby successive pulls of the cord will make and break said circuit.

10. In an electrical pull-cord socket of the character described including an insulating housing adapted to contain a switch mechanism for making and breaking an electrical circuit between a line and an electrical device, a switch mechanism including a fixed and movable contact mounted on the outside of said housing, the movable contact being biased into engagement with the fixed contact, each contact being connected to a part of the circuit and said movable contact being movable relative to said fixed contact for making and breaking the circuit, a rotatable detent member having the pull-cord thereto attached, a unidirectional rotatable wheel having ratchet teeth engageable by said member adapted to rotate the wheel in step-by-step movements with successive pulls of the cord, said wheel having a plurality of cam formations corresponding in number to the number of ratchet teeth, a reciprocable rod mounted in a wall of said casing having one end engaging the movable contact outside the casing and the other end engaging a cam formation, said cam formations being of a dimension whereby

11

alternate formations will cause said rod to be moved against said movable contact for moving said contact out of engagement with the fixed contact while intermediate formations permit movement of the rod in a direction permitting said movable contact to engage the fixed contact, whereby successive pulls of the cord will make and break said circuit, said detent member, wheel and plug being made from insulating material.

11. In an electrical pull-cord socket of the character described including an insulating housing adapted to contain a switch mechanism for making and breaking an electrical circuit between a line and an electrical device, a switch mechanism including a fixed and movable contact mounted on the outside of said housing, the movable contact being biased into engagement with the fixed contact, each contact being connected to a part of the circuit and said movable contact being movable relative to said fixed contact for making and breaking the circuit, a rotatable detent member having the pull-cord thereto attached, a unidirectional rotatable wheel having ratchet teeth engageable by said member adapted to rotate the wheel in step-by-step movements with successive pulls of the cord, said wheel having a plurality of cam formations corresponding in number to the num-

12

ber of ratchet teeth, a reciprocable rod mounted in a wall of said casing having one end engaging the movable contact outside the casing and the other end engaging a cam formation, said cam formations being of a dimension whereby alternate formations will cause said rod to be moved against said movable contact for moving said contact out of engagement with the fixed contact while intermediate formations permit movement of the rod in a direction permitting said movable contact to engage the fixed contact, whereby successive pulls of the cord will make and break said circuit, said detent member, wheel and plug being made from insulating material, and an adjustable plate member mounted over said movable contact for varying the tension thereof.

OTTO HOLZAPPFEL.
